CONTAINER

John Hohl, Westport, Conn., assignor, by mesne assignments, to Owens-Illinois Glass Company, Toledo, Ohio, a corporation of Ohio

Application December 30, 1936, Serial No. 118,293

14 Claims. (Cl. 229—53)

This invention relates to flexible-walled containers, particularly adapted for the storage, shipment and dispensing of various materials such as coffee, sugar, popcorn, confections and the like.

One object of the present invention is to provide a flexible-walled container having a new and improved seal, which may be easily and inexpensively formed to effect an hermetic closure, and which may be easily broken by simple finger manipulation, without rupturing, tearing or destroying the container.

As a feature of the present invention, the flexible-walled container is provided at one end with a pair of substantially opposed finger tabs extending from opposite panels of the container respectively and normally folded against these panels. These panels are bonded together across the end to form a closure seal which can be easily broken by merely pulling the opposed tabs apart. This manipulation causes the seal to be broken progressively from the center of the panels towards its sides, and simultaneously causes the two panels to be separated to form an opening through which the contents of the container can be readily discharged.

Various other objects, features and advantages of the invention will be apparent from the following particular description and from an inspection of the accompanying drawing in which:

Fig. 1 is a front elevation of a container embodying the present invention, and shown in collapsed condition after being sealed at one end and prior to being filled from the other end.

Figs. 2 and 3 are sections taken on the lines 2—2 and 3—3 of Fig. 1, respectively, but on a somewhat larger scale.

Fig. 4 is a perspective view of the container of Fig. 1 in inverted position and ready to be filled.

Fig. 5 is a perspective view of the container after it has been filled and completely sealed.

Fig. 6 is a perspective view of another form of container embodying the present invention, and

Fig. 7 is a section taken on line 7—7 of Fig. 6 but on a somewhat larger scale.

It must be understood that the thickness of the various wall layers of the flexible container is shown in this drawing somewhat exaggerated, and that in practice all of these layers are very thin.

The container shown in Figs. 1 to 5 inclusive, is made of laminated sheet material, the inner layer or coating of which is of such material that when portions of such inner layer are super-

posed and pressed together under heat, they will weld, vulcanize or hermetically unite. As an example of such material, I may and preferably do employ a type of thin, flexible, transparent, slightly elastic, impervious material sold under the name of "Pliofilm" and made from chlorinated rubber compound. This material has the thermoplastic characteristic of being readily vulcanized or sealed at a temperature of approximately 115° C., so that the overlapping sections thereof may be vulcanized or sealed together by the application of heat and pressure, even though the surfaces have been previously wetted by contact with liquids or moisture-carrying plastic material. Another material which may be satisfactorily used in some constructions and for some materials, is a moisture-proof cellulosic material of the type sold under the trade name "Heat Sealing Cellophane". As far as some aspects of the invention are concerned, a thin sheet material having a waterproof thermoplastic coating or layer such as that sold under the trade name "Koroseal", or a sheet material sold under the trade name "Parafilm" and having a coating of latex and paraffin, may also be used. Also, as far as certain aspects of the invention are concerned, other materials may be used, which may be fabricated into a casing by the use of an adhesive or a solvent to sealably secure adjacent surfaces of said material together.

The inner layer of the laminated sheet from which the bag is made will hereinafter be referred to as "Pliofilm" although it is to be understood that such a term, for the purpose of this invention, and as far as many aspects of the invention are concerned, may include any material of the type or character hereinbefore referred to.

In the specific construction shown in Figs. 1—5, the container is fashioned from a flexible laminated sheet comprising an inner layer 12 of Pliofilm and an outer reenforcing sheet 13, cemented or otherwise secured thereto and made of paper or other similar flexible sheet material which will not be injuriously affected by application of sufficient heat and pressure to effect sealing, fusing or vulcanizing of the Pliofilm. The longitudinal edges of this laminated sheet are sealed together in parallelism to form a flat tube having a longitudinal seam 14, and a pair of opposed panels integrally connected along their longitudinal edges.

The longitudinal seam 14 of the tube has opposed sections of the Pliofilm autogenously bonded together, and is so constructed as to prevent

- any peeling or separating action between said bonded sections due to internal pressure action on said seal. For that purpose, one longitudinal side of the outer paper layer 13 extends beyond the corresponding longitudinal edge of the inner Pliofilm layer 12 to form a marginal extension 15, and the opposite longitudinal side of said inner layer 12 extends beyond the corresponding longitudinal edge of the outer paper layer 13 to form a marginal extension 16. The marginal outer layer extension 15 is cemented or otherwise secured to the outer face of the opposite longitudinal side section of the outer sheet 13, and the marginal Pliofilm extension 16 is heat-sealed 15 to the inner face of the opposite longitudinal side section of the inner Pliofilm layer 12 to form an autogenous bond between said Pliofilm sections, said heat-sealing being effected by the application of heat and pressure.
- 20 Although the Pliofilm layer 12 is shown sealed together along its longitudinal edges, as far as certain aspects of the invention are concerned, said Pliofilm layer may be in the form of a seam-less tube.
- 25 As a feature of the present invention, the panels of the individual tubes are provided at their upper ends with flanges forming finger tabs by which said panels may be separated to form an opening. In the construction shown in Figs. 1-5 30 these flanges are formed by folding the tubes longitudinally to form pleats 20 and 21. The inner lapping Pliofilm layers of said pleats are heat-sealed together at least at the bases of said pleats and advantageously throughout their areas to 35 form strong well defined finger tabs, and said pleats are substantially triangular in shape so that the lower ends of said pleats gradually merge into the general contour of the container when it is filled as shown in Fig. 5. This triangular shape of the pleats also facilitates folding of said 40 pleats against the opposed panels of the container, as will be more fully described.
- In order to permit the formation of an hermetic seal across the top of the container, the two pleats 45 20 and 21 are offset a comparatively short distance from the opposite sides of the longitudinal center line of the tube respectively. As shown, the pleat 20 is offset to the right of this center line, and the pleat 21 is offset to the left of said 50 center line and these pleats are folded and pressed against the panels away from said center line so that there is formed between the bases of the two pleats a longitudinal section 22 having a thickness equivalent to the minimum thickness 55 of the flat tube so that sealing heat may be transmitted to the opposed Pliofilm layers of said section without interference from said pleats.
- The inner Pliofilm layers of the tube are autogenously bonded together at its upper end along 60 the lines 23 and 24 to form an hermetic seal across the top of the tube. The seal along the line 23 is effected by a heating element pressed directly against the front panel of the tube (Fig. 1) and co-operating with a suitable platen member 65 on the opposite or rear panel of said tube. This heating element extends obliquely along the line 23 from the left-hand side of the tube to the upper end of said tube, so that sealing heat is effectively transmitted to the inner Pliofilm 70 layer of the tube panels along said line at least up to the base of the pleat 20, without interference from said pleat.
- 75 For sealing the tube along the line 24 the heating element is pressed directly against the rear panel, (Fig. 1) and is backed by a platen member

acting against the front panel. This heating element extends obliquely along the line 24 from the right-hand side of the tube to the upper end of the tube, and crosses the center portion 22 of the tube so that the hermetic seal is effected at least up to the base of the pleat 21.

The seals along the lines 23 and 24 intersect approximately at the longitudinal center line of the tube, and conjointly form an effective unbroken hermetic seal across the entire width of the tube. Although this closure seal is shown as a line seal, the width of the sealed area may be varied in accordance with the sealing strength desired.

The lower end of the resultant container is 15 cut transversely as shown, and a simple seal may be formed there across by the application of heat and pressure to effect the autogenous bonding together of the opposed inner Pliofilm layers. Although this bottom seal is shown as a straight 20 seal it may be in any other suitable form without departing from the spirit of the invention. For instance it may extend along a section convexly curved with respect to the outside of the bag as 25 set forth in my co-pending application Serial No. 113,969, filed December 3, 1936.

The container as shown in Fig. 1 is sealed at the top and opened at the bottom, and in this condition it may be shipped to a distant point where it may be filled and then sealed at the bottom. The empty container is preferably shipped 30 in the condition shown in Fig. 1 since the bottom seal can be easily effected at any remote station, where the container is filled, while the upper seal requires a little more care to form and therefore 35 could be more easily effected at the place where the actual containers are made.

The container is filled from the bottom in the inverted position shown in Fig. 4, and said bottom transversely sealed at A by the application of 40 heat and pressure, to form a package which in its normal upright position, will be in the form shown in Fig. 5.

If desired, the outside paper sheet 13 may have a slit defining a hinged flap 25 which is un- 45 attached to the Pliofilm layer 12, and which may be lifted as shown in Fig. 5 to permit observation of the contents of the container through the transparent Pliofilm layer 12.

In order to open the container, all that is 50 necessary is to bend the pleats 20 and 21 into substantially vertical position with respect to the container panels as shown in Fig. 5, and pull these pleats apart. This manipulation results in peeling the panels apart along the seal 55 lines 23 and 24 and separating the opposed panels of the container, to form an opening through which the contents of the container may be discharged.

In Figs. 6 and 7 is shown another form of 60 container made from single-ply sheet material which has a waterproof coating or thermoplastic material on the inner surface thereof, and which may be similar to Parafilm previously referred to herein. In the construction shown two similar 65 sheets 30 and 31 of such material have their edges secured together by heat and pressure to form a tube having two seam flanges 32 and 33, extending the full length of said tube and forming finger tabs for the container. The tube is flat- 70 tened in such a way as to offset the two seam flanges 32 and 33 on opposite sides of the longitudinal center line of the tube, and said flanges are folded and pressed against the panels of the tube away from said center line.

The tube is sealed across the upper end thereof along seal lines 34 and 35 by the application of sealing heat from opposite panels of the tube in a manner already described with reference to the construction of Figs. 1-5. These seal lines 34 and 35 may extend obliquely so that they will intersect at the longitudinal center line of the tube as in the construction of Figs. 1-5, or may have their outer side portions extending in alignment with each other, and their inner side portions extending upwardly towards the upper end of the container so that they will intersect at the center line as shown in Fig. 6. In this manner an hermetic seal is formed across the upper end of the tube.

The lower end of the container may be left open to permit the filling of said container from the bottom. After the container is filled it is transversely sealed along the bottom section B to provide a permanent seal. The heat across the bottom of the container is made hot enough to permit the transmission of sealing heat through the folded seam flanges 32 and 33 to the inner thermoplastic layer of the container material. If desired, the bottom edges may be line sealed similar to the top.

The opening of the bag at the upper end is effected by bending the seam flanges 32 and 33 into substantially perpendicular position with respect to the container panels, and pulling these flanges apart to break the seal along the lines 34 and 35.

Although the containers of Figs. 6 and 7 are shown made from two sheets connected together at opposed edges, so far as certain aspects of the invention are concerned said container may be formed from a single sheet, and one of the finger tabs therefor may be formed by a pleating of said material, while the other finger tab is formed by a seam flange connecting the opposite edges of the sheet together as shown in Figs. 6 and 7. Also said sheets may be laminated with an inner layer of Pliofilm and the seam flange formed by the autogenous bonding of said layers.

By the term "flange" in the specification and claims herein is meant an extension integral with the panels of the container, and large enough to be grasped by the fingers for container-opening operation.

Having thus described my invention, what I claim as new and desire to secure by Letters Patent is:

1. A flexible-walled container having a pair of opposed panels bonded together at one end to form a seal, and a pair of finger tabs connected respectively to said panels at said end and disposed in approximately opposed relationship, whereby said seal may be broken and an opening formed at said end by pulling said tabs apart.

2. A flexible-walled container having opposite walls at least one of which presents an inner surface of thermoplastic material, whereby said walls may be sealed together, and having a pair of substantially opposed substantially triangular finger tabs carried respectively by said walls at one end of said container.

3. A flexible-walled container having a pair of opposed panels bonded together at one end to form a seal, and pleated respectively at said end at approximately opposed sections of said panels to form finger tabs.

4. A flexible-walled container having an inner surface of thermoplastic material, and having a pair of opposed panels folded at one end at approximately opposed sections to form a pair

of substantially triangular pleats large enough to be grasped by the fingers to pull said panels apart to open the container, each pleat having its juxtaposed layers bonded together by said material.

5. A container of flexible material having a pair of opposed panels bonded autogenously together along sections intersecting approximately at the longitudinal center line of said container to form a seal, and a pair of finger tabs connected to said panels and spaced respectively a short distance from opposite sides of said center line.

6. A flexible-walled container having an inner surface of thermoplastic material, and having a pair of opposed panels bonded together at one end, and having a pair of flanges offset a comparatively short distance from opposite sides of the center line of said container respectively.

7. A normally flat container of flexible material having an inner thermoplastic surface including a pair of similar opposed panels directly interconnected at their sides and hermetically sealed together at one end across the width of the container, said panels being flanged at approximately opposed sections thereof near said end to form finger tabs.

8. A normally flat container of flexible material, including a pair of similar opposed panels adapted to be sealed together and provided at their upper ends with a pair of flanges extending longitudinally of said panels respectively, and having their bases spaced a comparatively short distance from opposite sides of the longitudinal center line of the container respectively, said flanges being folded against their respective panels away from said center line.

9. A normally flat container of flexible material, including a pair of similar opposed panels adapted to be sealed together and provided with a pair of seam flanges extending longitudinally the full length of said panels, said flanges having their bases offset a short distance from the opposite sides of the longitudinal center line of the container respectively, and being folded against their respective panels away from said center line.

10. A flexible walled container having a pair of opposed panels sealed together at one end, and a pair of finger tabs connected to said panels at said end respectively and disposed in approximately opposed relationship, one of said finger tabs comprising a seam flange for the container material.

11. A container made from two similar sheets of flexible material having inner thermoplastic surfaces, said sheets being autogenously bonded together at opposite edges thereof to form a flat tube having a pair of substantially opposed seam flanges extending outwardly from the opposed panels of said tube, said panels being autogenously sealed together across one end of said tube.

12. A package including a flexible-walled container having a pair of similar opposed panels hermetically sealed together at the bottom and at the top, said panels having a pair of flanges respectively at the top in approximately opposed relationship serving as finger tabs by which the top seal may be broken and the two panels separated to form a discharge opening.

13. A flat collapsed flexible-walled container having parallel closely juxtaposed opposite side walls, each presenting an inner surface of thermoplastic material whereby said walls may

be bonded together, and said side walls having a pair of substantially opposed finger tabs connected respectively to said side walls at one end of said container.

5 14. A flexible-walled container having a pair of opposed panels folded at one end intermediate of

their side edges to form a pair of pleats large enough to be grasped by the fingers to pull the panels apart and means for sealing said panels together at said end.

JOHN HOHL.
